ATTORNEY.

UNITED STATES PATENT OFFICE.

JOHN T. LORD, OF LAWRENCE, MASSACHUSETTS, ASSIGNOR TO PACIFIC MILLS, OF LAWRENCE, MASSACHUSETTS, A CORPORATION.

BRUSH.

1,182,496.

Specification of Letters Patent.

Patented May 9, 1916.

Application filed January 29, 1916. Serial No. 75,130.

To all whom it may concern:

Be it known that I, JOHN T. LORD, a citizen of the United States, residing at Lawrence, in the county of Essex and State of Massachusetts, have invented certain new and useful Improvements in Brushes, of which the following is a specification.

My invention relates to brushes of the type wherein tufts of bristles are held in place in bristle holes in a bristle block by means of staples. Such brushes have been made with holes which enter but do not pass through a block of material into which staples may be driven, and they have been made with such holes in material which is so hard that the staples will not enter it but will be upset or bent so as to bear against the sides of the holes or to enter recesses therein. Brushes have also been made in two parts one being a bristle block through which bristle holes are made, in association with another block attached thereto into which the staples are driven.

Brush stapling machines for filling and refilling brushes with bristles such as are known as the Liebig filling machines have been used a great many years and it is for use with such machines that I have devised my novel brush.

My brush comprises a bristle block which is preferably of hard, durable material having a plurality of holes which extend therethrough from front to back. Each hole is adapted to receive a tuft of bristles from the front together with the staple which is to hold the tuft, and has medially therein a stop, such as an annular shoulder, which may be square or tapering or an annular rim. A removable plug of relatively soft material into which a staple can be driven is placed or preferably driven from the back into each hole up against the stop or shoulder therein and into each of these plugs is driven a staple holding a tuft of bristles.

The advantages of my construction are that the bristle block will last indefinitely as there is no chewing up resulting from the driving in of staples as they slip through the bristle holes and are each driven into a suitable plug. Besides this, when a tuft of bristles becomes worn, it with its staple can be pulled out from the front and a new staple with its tuft of bristles can be driven into the old plug. This process can be repeated until the plug wears out. When one

or more plugs have worn out, the staples can be withdrawn therefrom, the back plate of the brush, if one is used, can be removed, after which the worn plugs can be knocked out from the front and replaced by new 60 plugs. This can be done very rapidly and with no injury whatever to the other parts of the brush.

My construction is particularly useful for what is known as dabbing brushes used with 65 combing machines as with such brushes the wear comes mostly on certain parts thereof, and such parts must be frequently replaced.

In the drawings, Figure 1 is a perspective view of a dabbing brush or comb brush. 70 Fig. 2 is a sectional view of the bristle block thereof showing the holes, some with plugs in place and some without. Fig. 3 is a sectional view of the bristle block with a back plate in place, the whole being upside down 75 and in the position it is in when the tuft staples are being driven into place. Fig. 4 is an elevation partly in section of a hand brush with a metal back plate. Figs. 5 and 6 are sectional details showing different 80 forms of stops which can be used in the bristle holes without interfering with the driving of the staples.

A represents a bristle block with substantially parallel surfaces 10 and 11. 10, I will 85 call the front and 11 the back. Through block A, I bore a plurality of holes B each of which is larger at the back 13 than it is at the front 12. Medially of each hole there is therefore a stop consisting of an annular 90 shoulder 14. From the back into the part 13 of each hole B, I place, or preferably drive, a plug such as C until it is stopped by the stop 14 and I preferably make each plug of such length that its head will be flush 95 with the back 11 of the bristle block.

I prefer to make the bristle block of some hard, durable material such as aluminum, fiber or hard, close grained wood, while I prefer to make the plugs of some relatively 100 soft material into which a staple can readily be driven and of such character that it will retain the staple in place under ordinary conditions. A plug of soft wood is suitable for this purpose.

E, E represent tufts of bristles each of which is looped through a staple such as F in a well known manner. Each staple carrying a tuft is passed into and through the part 12 of a hole B and the staple F is 110

driven into a plug C as shown in the drawings.

In a dabbing brush such as shown in Figs. 1, 2 and 3, the lock block H attached to bristle block A at the back by means of bolts 20 and nuts 21 serves as a back plate to prevent the plugs C from being forced out through the back. To prevent the plugs being forced back into the bolt slot 22, I make 10 a shallow slot 23 extending beyond the bottom thereof on the inside and in this slot I insert a plate 24 of thin sheet metal as shown by the dotted lines in Fig. 1.

A dabbing brush is so used that the bristles are striking continually head on and there is a tendency to force the plugs out through the back. For such brushes, some sort of a back plate is quite necessary but for other purposes as for instance for use in a hand brush like that shown in Fig. 4, a bristle block H could be used with no back plate. However, I prefer in such cases to use a thin metal back plate such as K.

In Fig. 5, I show a bristle hole of which the front part 40 is cylindrical, while the back part 41 flares outwardly to prevent the plug 42 of frustum shape from being pulled out at the front.

In Fig. 6, the front part 50 and back part 30 51 of a bristle hole are of the same size and cylindrical but between them is an annular rim 52 which serves as a stop for the staple plug 53. If the bristle tuft E is thick and the opening in stop 52 is a little smaller, a 35 looped part of the tuft will bear on one side of stop 52, while the plug 53 bears on the other side, whereby the whole thing will be locked in place.

As shown in the right hand holes of Fig. 40 6 the annular rim 52 may be of the same material as and integral with the bristle

block, or, as shown in the left hand holes, the front part 50 and back part 51 of a bristle hole may be separated by a groove 54 into which may be forced a split ring or 45 washer 55 which projects enough to form a stop or annular rim.

The staple plugs may be longer than their holes when driven thereinto and their projecting ends may be cut off, planed or sanded down and thus made smooth and true after filling. The plugs may be glued into their holes although this is not necessary.

I claim:

1. In a brush, a bristle block having a plurality of holes which extend therethrough from front to back, each hole adapted to receive a tuft of bristles from the front and having a step which projects medially thereof, a plurality of removable plugs each of which fits into a hole from the back and rests against a stop, each plug being adapted to have driven therein from the front, a staple to retain a tuft of bristles in 65 its hole.

2. In a brush, a bristle block having a plurality of holes which extend therethrough from front to back, each hole adapted to receive a tuft of bristles from the front and 70 having a stop which projects medially thereof, a plurality of removable plugs each of which fits into a hole from the back and rests against a stop, each plug being adapted to have driven therein from the front, a 75 staple to retain a tuft of bristles in its hole, and a back plate attached to the back of the bristle block.

In testimony whereof I hereto affix my signature.

JOHN T. LORD.
